GUN SIGHT

Crawford C. Loomis, Ilion, N. Y., assignor to
Remington Arms Company, Inc., a corporation
of Delaware

Application May 22, 1937, Serial No. 144,138

4 Claims. (Cl. 33—58)

This invention relates to sights for firearms, and contemplates a highly compact and efficient sight of novel construction and provided with novel means for effecting vertical adjustment.

5 In the drawing:

Fig. 1 is a plan view of the sight.

Fig. 2 is a side elevation thereof.

Fig. 3 is a section substantially on the line 3—3 of Fig. 1.

10 Fig. 4 is a section substantially on the line 4—4 of Fig. 1.

Fig. 5 is a top plan view of an assembly nut.

The sight comprises a dovetail base 10 of conventional form adapted to be received in a groove 15 of corresponding shape in the barrel, receiver or tang, of a firearm. Projecting upwardly from the base 10 and rigidly secured thereto or integral therewith is a cylindrical post 11 which is threaded from its free end throughout the greater portion of its length and comprises a vertical centrally disposed slot 12 extending through its entire length and substantially separating the post into two counterpart halves. The slot 12 receives the flat blade-like shank 13 of a sight member identified generally by the numeral 14. The mid-portion of the lower end of the shank 13 is cut away to form projections 15 which are received in apertures 16 in the base 10 when the sight member is in its lower positions of elevation. The margins of shank 13 are threaded, the threads being received in a threaded aperture in an adjusting member identified generally by numeral 17. To facilitate manipulation thereof, the periphery of member 17 or any desired portion thereof may be roughened or knurled, as illustrated. The aperture in the adjusting member 17 is of sufficient diameter to clear the threaded post 11.

40 The threaded portion of post 11 receives an interiorly threaded assembly nut 18 comprising a slot 181 (Fig. 5) which receives a widened portion 19 of the shank of the sight member 14, whereby the nut is held against rotation on the post. The portion of the sight member extending above the part 19 is formed into a sight comprising a sight surface of any desired character. For the purpose of illustration, a conventional curvilinear notched sight 20 has been shown, but it will be understood that any one of a wide variety of sights may be used. Preferably, although not necessarily, the adjusting member 17 comprises an upwardly extending skirt 21 partially enclosing the assembly nut 18, and the upper ends of skirt 21 and nut 18 may be beveled inwardly, as shown in Fig. 3. A reference mark 22

may be placed on any non-rotating part, such as the assembly nut 18, and the rotatable adjusting member may comprise elevation indicating graduations 23 which may conveniently be placed upon the beveled portion of the skirt 21 adjacent the beveled portion of nut 18. Any suitable "click" arrangement may be provided; for example, the under-surface of adjusting member 17 may comprise a series of recesses 24 conforming in spacing to the graduations 23 and adapted to receive a spring-pressed locating member 25 partially housed in a recess 26 in the base 10. The rear side of part 19 of the sight member may likewise comprise graduations, indicating its elevation with respect to the top of assembly nut 18.

15 From the foregoing description, it will be apparent that, the parts being assembled in the manner illustrated in Figs. 3 and 4, rotation of the adjusting member 17 in one direction will elevate the sight member, while rotation of the 20 adjusting member in the reverse direction will lower the sight member. To prevent accidental removal of the sight member, by over-rotation of the adjusting member in the direction of elevation, one side of the shank of the sight member 25 may comprise a shallow recess 27 adapted to receive the end of a retaining screw 28 threaded into an aperture in the assembly nut 18. Skirt 21 of the adjusting member 17 comprises a cut-out 29 to permit the insertion and removal of 30 the screw 28. In its final position, the head of screw 28 lies within the periphery of assembly nut 18, this being necessary to permit rotation of the adjusting member 17.

In assembly, the adjusting member 17 is 35 dropped over the post 11 and the assembly nut 18 is then screwed onto the post 11 to correct position, the slot therein being aligned with the slot 12 in the post 11. The sight member is then 40 inserted into these slots until the ends 15 thereof contact the threads of the aperture in the adjusting member 17. Rotation of said member effects engagement of these threads, and the sight member may be lowered by such rotation to any desired position. The cut-out 29 is aligned with the 45 aperture in nut 18 which receives the screw 28 and said screw is put in place, its point engaging the recess 27 in the sight shank.

50 The invention is not to be considered as limited to the embodiment illustrated and described herein, which embodiment is to be understood as typical and representative only, the invention being susceptible to many modifications all falling within the scope of the appended claims, which claims are to be broadly construed.

What is claimed is:

1. In a firearms sight, a sight member comprising a sight surface, a widened flat blade-like body depending from said sight surface, and a flat blade-like shank of less width than said body and depending from said body, the margins of said shank being threaded. 5
2. In a firearms sight; a sight member comprising a sight surface, a widened flat blade-like body depending from said sight surface, and a flat blade-like shank of less width than said body and depending from said body, the margins of said shank being threaded; a holder for said sight member comprising a dovetail base, a threaded 10 post integral with and projecting upwardly from said base, said post being slotted to receive said sight shank and a portion of said sight body, a sight adjusting member comprising a member having a recess and a concentric threaded aperture adapted to pass over said post and for engagement with the threads of said shank projecting from said slot, and an assembly nut received in said recess and having thread engagement with said post. 15
3. A firearms sight comprising a base adapted for attachment to a firearm, a threaded post rigidly secured to and projecting upwardly from said base, said post having a vertically disposed slot having flat margins intersecting the periphery of said post on opposite sides thereof, a sight member comprising a flat shank adapted to be 20 received in said slot and to project laterally therefrom, threads on the laterally projecting portions of said shank, a recessed sight adjusting member having a threaded aperture concentric with said recess adapted for engagement with the threads of said shank, and means for retaining said sight adjusting member on said post for rotation only comprising an assembly nut in the recess in said sight adjusting member threaded to said post. 25
4. A firearms sight comprising a base adapted for attachment to a firearm, a threaded post rigidly secured to and projecting upwardly from said base, said post having a vertically disposed slot having flat margins intersecting the periphery of said post on opposite sides thereof, a sight member comprising a flat shank adapted to be 30 received in said slot and to project laterally therefrom, threads on the laterally projecting portions of said shank, a recessed sight adjusting member having a threaded aperture concentric with said recess adapted for engagement with the threads of said shank, means for retaining said sight adjusting member on said post for rotation only comprising an assembly nut in the recess in said sight adjusting member threaded to said post, and means for limiting the adjustment of said sight comprising a screw threaded into said assembly nut, there being a vertical recess in said sight member adapted to receive the end portion of said screw. 30
